UNITED STATES PATENT OFFICE

CHARLES P. HESS, OF CLEVELAND, OHIO

ANTICREEPER FOR RAILS

Application filed February 11, 1931. Serial No. 515,107.

In railroad building it is well known that it is necessary to prevent displacement of the rails, and for this purpose it is customary, as is well known, to provide anti-creeping devices for the prevention of longitudinal creeping or traveling of the rails in use, as well as the securing spikes which hold the rails to the cross ties to prevent lateral displacement thereof. These anti-creeping devices are placed on each side of each cross tie and are adapted to tightly clamp the rail flange against the cross tie in such manner that the anti-creeping devices will not be liable to become loosened or removed from the rails but will always form a binding action with such rails.

The present invention relates to an improved form of such anti-creeping devices which is featured by ease of manufacture and application to the rails and also by the provision of new and improved instrumentalities for interlocking the complementary parts of the device.

The invention will be more readily understood by reference to the accompanying drawings in which Fig. 1 is a perspective view of an anti-creeping device formed in accordance with this invention.

Fig. 2 is a top plan view of the device of Fig. 1, indicating in dotted lines the displaced position of the complementary members of which the device is formed, and indicating by arrows the relative direction of travel of the complementary members when they are brought to interlocking position.

Fig. 3 is a bottom plan view of the device of Fig. 1.

Fig. 4 is an end elevation of the device of Fig. 1.

Fig. 5 is a perspective view of one of the members of which the device is formed.

Fig. 6 is a perspective view of the other member adapted to interlock with the member of Fig. 5.

Fig. 7 is a detailed perspective view showing the device applied to a rail as installed for operation; and

Fig. 8 is a diagrammatical plan view of a section of railroad track showing the application of the device of this invention.

As will readily be seen from an inspection of the drawings, the anti-creeping device of the present invention comprises two complementary interlocking members 10 and 11 which are designed to bear against the lateral edges of the base of the rail 12 and to cooperatively exert a clamping action thereon. In addition to the lateral clamping action the member 10 exerts a vertical gripping action upon the upper and lower faces of the contiguous portion of the rail bases, which action materially reinforces the engagement between the anti-creeping device and the rail.

The gap of the jaw 10 is provided with opposing rail engaging faces 13 and 14 which lie flat against the respective upper and lower surfaces of the rail flange or base against which they bear. The faces 13 and 14 bear firmly against the top and bottom of the contiguous portion of the rail flange respectively and exert a gripping action upon the rail, and because of this gripping action, the creep of the rail tends to carry the member 10 with it.

It will be seen that the jaw 10 is provided with a downwardly curved portion 15 which abuts against the tie, designated 16, and the tendency of the jaw 10, and more specifically the upper portion thereof to move with the rail, together with this abutment of the lower portion 15 thereof against the tie and restraining such movement results in a kind of rocking movement of the member 10 which causes the faces 13 and 14 to more firmly bear against the upper and lower faces of the rail base and to increase the vertical gripping action of the member 10 upon the rail flange. This action may be increased by placing the contact point of the upper face 13 with the rail somewhat in advance of the contact point of the lower face 14.

Interlocking with the member 10 is the member 11, forming a complementary member therefor and provided with rail engaging faces 17 and 18 similar to the faces 13 and 14 above described. This member 11 is formed with a depending portion 19 of configuration similar to the portion 15 of the member 10 and adapted to fit therein, so that the face 20 of the member 11 will abut the

face 21 of the member 10, the portions 15 and 19 being prevented, because of their complementary configurations, from lateral displacement.

- 5 It will be seen that the member 11 is provided with a strong spring member 22 provided with a downturned rib 23, which rib is adapted to progressively engage the notches 24 in the face 21 of the member 10. The action of this spring is such that while permitting the member 11 to be slipped into the member 10 with ease, yet, because of the interengagement of the rib 23 with the notches or grooves 24, accidental displacement of the members 10 and 11 will be prevented and these members will be securely interlocked together.

20 This invention is also characterized by the fact that the members 10 and 11 are joined together at an oblique angle, as is clearly shown in Figs. 1, 2 and 3, so that the distance between the jaws of the members 10 and 11 will be greater as these members are displaced than will be the distance between the 25 jaws when the members are in the position shown in Fig. 1. This permits a very close engagement between the anti-creeping device and the rail and holds the device securely and immovably clamped to the rail, although the members 10 and 11 may be readily released from their interlocking engagement by pressure exerted upon the spring 22 to raise this 30 spring and thus release the rib 23 from engagement with the notches 24. This rib 23 acts as a pawl, the notches 24 serving as a rack therefor, this structure permitting the ready slipping together of the members 10 and 11, as above described, but which prevents the accidental displacement thereof, the oblique angle between the parts 10 and 11 assuring permanent and rigid clamping 40 at all times between the anti-creeping device and the rail and tie so that longitudinal displacement of the rail will be entirely avoided.

45 The device is constructed of metal of suitable strength and hardness, and it is desirable that the weight of the device be kept as low as possible. For this reason, the final notch 24a is considerably larger than the remaining notches, a considerable amount of metal being cut away to form this notch, with corresponding decrease in weight. The weight of the device may be further decreased by making the outside surface of the 50 member 10 in the form of a channel.

It will be observed that the portions 15 and 19 of the respective members 10 and 11 are substantially U-shaped in their configuration, the portion 19 being adapted to fit into the portion 15 which therefore forms an outer portion of the complementary U-shaped members, the member 15 being provided with a depending interlocking flange 25 which is inserted in the U of the inner portion 19. 60 This cooperating complementary construc-

tion results in the production of an even flat surface 26 upon which the rail 12 engages. The construction which results is very simply made and is very strong and rigid.

It will be apparent that various changes in the details of the construction of this device may be made without departing from the inventive concept, and such changes will be apparent to one skilled in this art. It will be accordingly understood that it is intended and desired to embrace within the scope of this invention such modifications and changes as may be required to adapt it to varying conditions and uses.

Having thus described my invention, what I claim as new and desire to secure by Letters Patent of the United States is:

1. An anti-creeper for rails comprising a pair of separable complementary members adapted to interlock with each other to clamp with a rail and to abut against a cross-tie, and cooperating interlocking instrumentalities carried by the members, the instrumentalities comprising a series of grooves on one of the rail gripping members and a resilient pawl member carried by the other member for engaging with the grooves for interlocking therewith to prevent accidental displacement of the rail gripping members, while permitting ready interlocking thereof in rail clamping position.

2. An anti-creeper for rails comprising a pair of complementary rail gripping members adapted to interlock with each other to clamp with a rail and to abut against a cross-tie, and cooperating interlocking instrumentalities carried by the members, the instrumentalities comprising a series of grooves on one of the rail gripping members and a spring carried by the other member, the spring being provided with a downturned rib for engaging with the grooves for interlocking therewith to prevent accidental displacement of the rail gripping members, while permitting ready interlocking thereof in rail clamping position.

3. An anti-creeper for rails comprising a pair of complementary rail gripping members each provided with depending substantially U-shaped portions, one of which is adapted to be inserted into the other, the outer portion being provided with a depending interlocking flange for engaging the interior of the U of the inner portion to interlock therewith, the said U-shaped portions forming snugly inter-fitting channels and means for interlocking the said portions and members together.

4. An anti-creeper for rails comprising a pair of complementary rail clamping members provided with mutually interlocking substantially U-shaped portions and presenting a continuous uniformly flat rail engaging surface for uniform contact with a rail to which the members are clamped, and in-

terlocking instrumentalities carried by each member to mutually interlock the members for prevention of accidental displacement thereof while permitting ready interlocking of the members in rail-clamping position.

5. An anti-creeper for rails comprising a pair of complementary rail clamping members, one of which members is provided with a rail-engaging portion having a substantially flat rail-engaging surface and an upstanding rail engaging flange adapted to grip one edge of a rail, the said member being also provided with a generally downwardly extending portion formed to first extend downwardly, then curved upwardly and outwardly and thence inwardly and downwardly, thereby forming one part of an interlocking channel, the other of the said rail-engaging members having also an upstanding rail-engaging portion adapted to grip the other edge of the rail and having a substantially flat rail-engaging portion, the member having also a portion adapted to snugly fit into the generally downwardly extending portion of the first mentioned member and formed to first extend downwardly, then curved outwardly and upwardly, the flat rail portions of said members cooperating to form a continuous flat surface, and interlocking instrumentalities for locking the clamping members together.

In testimony whereof I affix my signature.
CHARLES P. HESS.
